5 Claims. (Cl. 244—1)

This invention relates to improvements in aerodynamic vehicles and more particularly to a method and mechanism for producing trim lift and side force on a re-entry vehicle utilizing separated flow induced by a blunt flare.

Due to the present scientific and other interest in recovering aerodynamic bodies from space flight, considerable emphasis has been placed on constructions of re-entry vehicles. The practical achievement of flight speeds of space vehicles through air causes aerodynamic bodies to burn through friction created by movement through the air at high speeds, i.e., aerodynamic heating as occurs on meteors, unless special means are taken to prevent this burning. One effective way of reducing or eliminating burning is to increase the aerodynamic drag of the vehicle in proportion to its weight. This increase in aerodynamic drag can clearly be achieved through the use of flares or body flaps on the body. This known construction reduces the cooling requirements and the amount of burning and also acts to stabilize the vehicle in flight somewhat in the same fashion as a badminton shuttlecock is stabilized by its flared feathers.

The beneficial effect of a body flare in preventing burning due to aerodynamic heating increases as the flare angle increases as long as the aerodynamic flow follows the body contours smoothly and does not separate therefrom. However, with a blunt nosed capsule and with a sufficiently large flare angle, the flow will separate. It is known, both theoretically and experimentally, that flow separation reduces the cooling load in a separated flow region to about one-half that for unseparated flow. Such reduced cooling load is a result of the reduced velocities of the airflow in the proximity of the body. Separation also has the effect of reducing the static pressure acting on the flare in the region of separation below that which would act in the same region with attached flow and below that which acts on the reattached area of the flare. By suitable control over the extent of the reattached flow area on the flare by the means outlined in this application, the separation can be made to yield further benefits, in addition to those of reduced cooling load, of enhanced stability and of the production of control forces for the purposes of maneuvering. Accordingly, it is the object of this invention to provide a maneuverable aerodynamic re-entry vehicle including blunt capsule and flare, which vehicle has increased stability and requires a decreased heat load accomplished by controlled use of flow separation, thereby achieving a weight saving since the weight of the cooling system or cooling material is reduced and the size of the flare may be reduced.

It is also an object of this invention to provide a means for producing trim lift and side force on an aerodynamic body for maneuverability by utilizing separated flow induced by a blunt flare by controlling the pitch and yaw angles of a flare axis relative to a capsule axis.

Other objects and advantages of this invention will be pointed out in the following description and claims and illustrated in the accompanying drawings, which disclose, by way of example, the principles of this invention and the best mode which has been contemplated of applying these principles.

In the drawings:

FIG. 1 is a diagrammatic illustration of a blunt capsule and rigidly attached flare type of aerodynamic body illustrating separation of flow;

2

FIG. 2 is a somewhat schematic illustration of the maneuverable aerodynamic vehicle of this invention with a portion broken away to show a capsule attached to a flare by means of a joint allowing limited universal movement therebetween;

FIG. 3 is an end view illustrating the areas of attached flow and the location of the center of gravity relative to the center of pressure of the capsule and flare; and

FIG. 4 is a view similar in nature to FIG. 3 illustrating trimmed lift and sideforce as well as positive dihedral effect.

In general, this invention contemplates controlling and stabilizing an aerodynamic body such as a re-entry vehicle. The body is constructed with a blunt nosed capsule and an attached rear flare. The flare is not rigidly attached to the capsule but is attached thereto by means of a suitable universal movement permitting joint such that the capsule may pitch and yaw relative to the flare. By means of this construction and using the principles of separated flow, as well as correctly locating the center of gravity and the like, the pitching and yawing moments caused by the lift and sideforce produced by flow separation and reattachment on the flare and caused by the lift and sideforce on the capsule due to its movement relative to the flare will compensate and permit trimmed stable flight of the vehicle, which can be maneuvered by moving the longitudinal axis of the flare relative to the longitudinal axis of the capsule. The resultant construction is an aerodynamic vehicle adapted for atmosphere re-entry purposes which requires minimum cooling due to separated flow, and utilizes the reattachment of separated flow for maneuverability, while having inherent aerodynamic stability.

Referring now to FIG. 1 for an understanding of the background of the invention, FIG. 1 shows an aerodynamic body 10 having a blunt nose 12 on a capsule or substantially cylindrical body portion 14. Rigidly joined to the body portion is a rear flare 16. This construction increases the aerodynamic drag with respect to the weight of the vehicle and helps prevent aerodynamic burning. A separation of flow is illustrated in FIG. 1 for a zero angle of attack. It can be seen that the flow separates at points S₁ and S₂ and reattaches itself to the flare at points R₁ and R₂ at the shoulder of the flare. The area of the triangle between S₁, R₁ or S₂, R₂ and the surface of the vehicle 10 is an area of separation of flow in which the static pressure acting on the body is greatly reduced and the cooling requirements are greatly reduced since there is no great friction created by the air rapidly moving over the body at this area. It is known that a favorable consequence of flow separation of this type is the fact that the total heat transfer in the separated regions is about half of what it would be for attached flow for both laminar and turbulent boundary layers. When the body illustrated in FIG. 1 is displaced from an equilibrium position of zero angle of attack, the separation of flow will be greater on one side than on the other side of the vehicle. On the side of least separation, there will be a greater area of reattached flow on the flare. The static pressure acting on the reattachment area will be greater than in the separated region. As a result the flare will produce a force behind the center of gravity which tends to pitch (or yaw) the vehicle so that motion of the flare is from the side of lesser separation to that of greater separation. It is clear that the forces developed on the flare tend to oppose the displacement for zero angle of attack which brought about the asymmetrical separation distribution. In this sense the flare produces stabilizing moments. However, in the displacement from zero angle of attack the force on the capsule will develop a moment about the center of gravity which will not tend to oppose the displacement

from zero angle. In this sense the capsule produces destabilizing moments. To achieve stability for a given capsule, it is only necessary to make the flare sufficiently large and blunt. Thus, to achieve favorable stability effects with flare-induced separation, it is necessary to control the center of gravity with respect to the two moments and the other geometrical variable such as the length of the flare, the magnitude of the flare angle, and the length of the body between the nose and the flare so that the forces created will balance.

Referring now to FIG. 2, a capsule portion 20 which houses a man or other payload is followed by a flare portion 22 which may be radiation cooled. The capsule 20 and flare 22 are joined together by a universal movement permitting joint 24. The illustrated type of universal movement joint 24 includes a plurality of actuating rods 26, 28, 29 activated by suitable servo motors (not shown) within housing 30, which in turn is rigidly supported from capsule 20 by support 32. The outer ends of the actuating rods are attached to the flare 22 to cause movement thereof. The means of attachment may include slotted brackets 34, 36, etc., mounted on the inside of flare 22. Of course, alternate constructions of controlled universal movement permitting joints could be utilized within the spirit of this invention. With a universal joint the capsule and flare may move relative to one another to pitch the capsule relative to the flare to obtain lift control and to yaw the capsule relative to the flare to obtain sideforce control.

Lift control is accomplished by utilizing the larger area of reattached flow at the bottom of the capsule as viewed in FIG. 2 behind the point R_2 to create an upward force on the capsule at this point, that is, a counterclockwise movement about the center of gravity point C.G. The capsule is pitched upwardly so that the cone of separation of air flow creates the reattached flow portion more on the bottom than on the top and, of course, the surface pressures are greater at the reattached flow area than at the separated flow region. For aerodynamic reasons the axis of the cone of separation is aligned in the free stream direction and the point of reattachment R_1 is at the shoulder of the flare. The differential pressures on the flare tend to turn the nose of the entire vehicle downwardly, i.e., produce a counterclockwise moment about the center of gravity. However, the capsule is pitched upwardly and this will cause lift to create an upload tending to turn the capsule clockwise about its center of gravity. When the pitching moment due to lift on the capsule balances that due to the lift on the flare, a trimmed condition is reached. Trim is an essential feature of practical control and by suitably controlling the angle of the axis of the flare with respect to the capsule, useful lift for maneuvering the vehicle may be produced.

Not only can trimmed lift be obtained for practical control, but also trimmed sideforce can be produced. Reference may be made to FIGS. 3 and 4 for an illustration of the method of producing combinations of trimmed lift and trimmed sideforce for maneuverability. FIG. 3 represents a front view of the vehicle with the capsule pitched in such a fashion as to cause lift but no side force. The shaded area R represents the area of reattached flow on the flare. The impact pressures of the reattached flow regions of the flare are, of course, greater than those in the separated flow region. The positive lift on the flare represented by the disposition of the crosshatched area produces a nose-down moment about a lateral axis through the center of gravity which just "trims" the nose-up moment due to the lift of the capsule.

To produce sideforce to the right the capsule must not only be pitched upward relative to the flare but also laterally, as shown in FIG. 4. The reattachment area is now disposed more to the left than to the right so that a sideforce to the right will be produced by the impact pressures on the reattachment area as well as by the static pressures

70
75

on the capsule. The vehicle will thus move toward the right in response to the side forces. There will be an alteration in the vehicle attitude, principally in its bank attitude, until the yawing moment about a vertical axis through the center of gravity induced by the impact pressures on the flare will just balance the equal and opposite yawing moment due to the forces on the capsule. In this new banked condition, the nose-up moment due to the capsule and the nose-down moment due to the flare may no longer balance. Thus the vehicle may also change its pitch attitude as well as its bank attitude so that the net pitching moment for the vehicle will also be zero. It is thus through the motion of the capsule with respect to the flare both in pitch and yaw that trimmed lift and sideforce for maneuvering are produced.

Consider now how a vehicle can be designed to possess positive dihedral effect. While positive dihedral effect is not necessary for an automatic control system, it is desirable in case of pilot control. The vehicle is designed so that the flare is a body of revolution, the center of gravity of the vehicle is close to the flare axis (on the flare axis extended), and the capsule exhibits generally larger lateral extents than vertical extents in its cross sections. Consider now FIG. 3, with the capsule deflected upward with respect to the flare in a trajectory descending in a vertical plane toward the earth. Under these circumstances the capsule will be trimmed in pitch and it will have zero yawing moment and zero rolling moment on it by symmetry. It can now be shown that if the capsule is displaced slightly about its longitudinal flare axis, it will right itself into the upright position and will not roll over on its back. Referring now to FIG. 4 with the whole vehicle slightly displaced from its equilibrium position, the forces which tend to produce rolling moments are those associated with the capsule solely. No rolling moments can be expected from the flare, a body of revolution, since all pressures acting on it act normal to its surface and through its longitudinal axis.

It is clear that the lift or normal force will have a tendency to return the capsule to an upright position, whereas the sideforce being positive to the right will have a tendency to roll the capsule over on its back. The magnitude of the lift as compared to the sideforce is controlled by properly shaping the capsule cross section to provide requisite lift and thereby controlling this righting tendency. In particular the aerodynamic configuration is such that the lift force per unit angle of attack is considerably larger than the sideforce per unit angle of side slip causing a righting tendency which will return the capsule to the upright position. To accomplish this aerodynamically, the capsule is simply made greater in the horizontal dimension than in the vertical dimension, generally speaking. Of course, the flare 22 does not have to be circular in section as there are a number of other cross sectional shapes for producing the same result.

Thus applicant has disclosed a method and means of stabilizing an aerodynamic body of the type having a blunt capsule and a flared portion to control the trim as well as the side force, while stabilizing the body about a longitudinal axis.

While there have been shown and described and pointed out the fundamental novel features of the invention as applied to the preferred embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. A maneuverable vehicle for travel in a fluid stream, said vehicle having a center of gravity, comprising:
a capsule;
nose means coupled to said capsule upstream of said

center of gravity for coacting with said fluid stream as said vehicle travels therein; control means coupled to said capsule downstream of said nose means, said control means having a surface extendable externally from said capsule for cooperating with said nose means to create an area of separated flow adjacent to said capsule, said flow defining a substantial conical surface of separation having a virtual apex in the vicinity of said nose means and defining a closed curve of attachment as said conical surface of separation intersects said control surface, said closed curve being so disposed along said control surface to substantially balance about said center of gravity all aerodynamic moments on said vehicle for providing substantially zero net moment about said center of gravity when said control means surface is in a neutral position; and coupling means for displacing said control means surface from its neutral position to at least a second position to alter said area of separated flow whereby at least a portion of said curve is displaced to a second location on said surface for providing moments about said center of gravity to produce attitude control and

- maneuverability when said vehicle travels in said fluid medium.
2. The combination of claim 1 wherein said control surface is substantially conical.
  3. The combination of claim 2 wherein said coupling means includes a universal joint between said control means surface and said capsule for providing universal motion of said control means relative to said capsule.
  4. The combination of claim 3 wherein said nose means has a blunt profile.
  5. The combination of claim 4 wherein said capsule is substantially cylindrical.
